Assignor to

Edward C. Sampson of New York City

Letters Patent No. 2443. Dated Sept. 25. 1866.

Design for a Floor Oil Cloth Pattern

The Schedule referred to in the Letters Patent and making part of the same.

To all whom it may concern.

Be it known that D. Charles J. Meyer of the Town of Bergen County of Hudson and State of New Jersey, have invented or produced a new original and ornamental Design or Pattern for Floor Oil Cloth Carpets and other Fabrics; and I do hereby declare that the accompanying drawing marked and designated as Exhibit No. 3, fully represents said design and is sufficient without further aid to enable any person skilled in the art to which it appertains to repeat it for practical use. — The colors and the arrangement of them, may in the use of this design be varied to suit the views or fancy of the user, or manufacturer of articles ornamented by said design. —

This Design may be of any size or color in kind or number, or in any contrast or blending of color of light and shades.

Claims new and desires to secure by Letters Patent of the United States, The Design for Floor Cloths, Carpets &c. as shown and described.
